UNITED STATES PATENT OFFICE.

WILLIAM A. SPENCER, OF LYNCHBURG, TENNESSEE.

WASHING-MACHINE.

SPECIFICATION forming part of Letters Patent No. 224,238, dated February 3, 1880.

Application filed November 8, 1879.

To all whom it may concern:

Be it known that I, WILLIAM A. SPENCER, of Lynchburg, in the county of Moore and State of Tennessee, have invented certain new and useful Improvements in Rocking Steam-Washers; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation of my rocking steam-washer. Fig. 2 is a vertical central sectional view of the same, and Fig. 3 is an interior plan view.

My invention relates to rocking steam-washers for articles of clothing and the like; and it consists in the construction and arrangement of parts, as will be fully set forth in the following description, and particularly pointed out in the claim.

In the drawings, A designates a casing, which is divided by means of partitions into the three compartments A' B B, the compartment A' being closed by a hinged cover, C, while the two remaining compartments B B are left open, as shown.

The compartment A' contains the rocking cage D, in which the clothes to be steamed are placed, and the compartments B are designed to contain water for the purpose of rinsing the clothes after they have been suitably steamed in the aforesaid cage. This cage is composed of a frame with wires secured thereto, so as to form a cylinder with openings for the admission of steam, and a longitudinal opening, d, through which the clothes may be passed into or taken out from the cage. It is also provided with end journals, which are journaled in the sides of the casing A, and is rocked during the steaming process by means of a crank-handle, E. This handle is adapted to fit upon one of the journals, so that it may be unshipped when desired, and its movement is limited by a stop, F, secured upon the casing so as to prevent an entire revolution of the cage. Within the compartment A' are arranged the false sides G G and a false bottom, H, space being left between these said

parts and the inner walls of the casing for water and steam.

The false bottom is provided with downwardly-opening valves I I for the admission of water into the space below the same, and the false sides are provided with perforations K for the passage of steam to the main compartment A'. The false sides and bottom are made removable from the casing, and are held in place during use by means of suitably-arranged cleats b and latches a.

L designates a packing upon the sides and partition which surround the compartment A', so that when the cover is down any unnecessary escape of steam will be prevented.

The compartments B B, in which the clothes are rinsed, are provided with removable false bottoms M, which are perforated, so as to allow the dirt to settle within the perforations. 70

All three of the compartments are provided with outlets or stop-cocks for the purpose of drawing off the water, that of the compartment A' being arranged to lead from the space below its false bottom.

N designates hooks, which are hinged to the casing so as to engage with eyes upon the cover C, in order to hold the same down during the process of steaming.

O represents a pipe leading from the cover, 80 and to this pipe I propose attaching a hose, so as to carry off steam and inject it into water either in the rinsing compartments B B, or into any adjacent vessel, whereby the temperature of the water within the same may be 85 raised in a most economical way.

In operation, the casing is placed upon an ordinary stove or furnace, or, if desired, a furnace may be specially constructed so as to heat the casing only under compartment A', 90 thus avoiding the necessity of the operator approaching too near the fire. The clothes are placed in the cage and water poured into the compartment A', from which it will pass through the valves into the space below its 95 false bottom. When the water becomes sufficiently heated its expansion will close the valves, and the steam arising between the false sides and the casing will pass out through the perforations into the compartment A' 100 against the clothes within the cage. During this operation the cage should be rocked, so

as to agitate the clothes and thoroughly present them to the action of the steam.

When the water is partly exhausted below the false bottom, and the water from the condensation of the steam exerts a greater pressure upon the valves than exists below the same, they will open, so that the water will flow back into the said space, where it is re-heated and again converted into steam.

10. What I claim as new is—

The casing A, with the steaming-compartment A', having a false bottom with downward-opening valves and removable false sides with perforations for the passage of steam

15 into the main compartment, spaces being left between the casing and said false sides and bottom for water and steam, and a rocking cage being arranged within the compartment A', substantially as herein shown and specified.

20 In testimony that I claim the above I have hereunto subscribed my name in the presence of two witnesses.

WILLIAM ALFRED SPENCER.
